UNITED STATES PATENT OFFICE

2,085,075

CRANKCASE FLUSHER AND CLEANER

James K. Delano, Poughkeepsie, N. Y.

Application January 8, 1936, Serial No. 58,135

6 Claims. (Cl. 184—1.5)

This invention relates to an apparatus, semi-automatic in its action for cleaning and flushing out the interiors of crank-case pans of internal combustion engines, such as automobile engines and the like, and constitutes an improvement over that described in my patent on a Crank and gear case cleaning apparatus, No. 2,041,529, issued May 19, 1936; and my application for a patent on a Method of cleaning crank-cases and the like, Serial No. 12,169, filed March 21, 1935.

In the various methods now devised for cleaning crank-cases, there are found certain types of apparatus which inject and withdraw the cleaning fluid from the case, usually by manually operated valves, which are necessarily slow in operation, or else they are connected to a motor driven pump, which is alternately reversed to inject or withdrawn the fluid.

It is also necessary to clean the withdrawn fluid before reinjecting it, and heretofore it has been the custom to allow the fluid to clean itself by filtering, which takes time to accomplish, so that it required a large volume of fluid in storage for cleaning, or else the cycles of injection and withdrawals are few and slow, due to both the time it takes to reverse the direction of the pump flow by manually operating the valves, or time it requires to pass through the filtering medium.

It is very important that after an injection the withdrawal take place immediately, as the stirred up sediment is usually of a heavy nature, containing particles of metal, hard carbon, fine sand, etc., which will settle very quickly, and if the withdrawal does not take place while the dirt is in suspension, very poor cleaning results.

It is important also that a crank-case be cleaned as quickly as possible from a commercial standpoint, so that the car will not be held up too long during the cleaning operation. By my method of timing, and the apparatus herein shown, I am able to within 20 seconds inject and withdraw a charge of cleaning fluid, and on the withdrawal, to filter it and immediately inject it again, and this can be repeated so that in a very few minutes the case is clean.

I have also devised means whereby the injections and withdrawals are of a positive nature, and the withdrawals follow the injections in an instantaneous manner and do not give the dislodged sediment any time within which to settle, and thus all of the dislodged sediment is withdrawn with the cleaning liquid.

It is also important that the cleaning liquid be separated from all of the foreign matter which has become mixed with it after each withdrawal from the pan, and to accomplish this, I have provided a centrifuge strainer through which the liquid passes, and which will effectively remove all of the heavy particles of dirt, grit, and foreign

matter therefrom; the centrifuge due to its high rotative speed forces the cleaner liquid through a renewable heavy felt bag, which retains the grit, etc., which can be renewed from time to time, or which can be cleaned and reinstated.

Also to provide for the most effective use of the liquid, it must be employed in a heated state, and this is accomplished by the use of a heater (here shown as electrically operated) which is immersed in the liquid container of the apparatus.

As before stated, to provide the most efficient and quickest method of removing and cleaning the sediment from the crank-case pan, it is important that the injections and withdrawals follow each other with great speed and without loss of time within which the sediment could again settle, and this has been accomplished by the use of a single pump in connection with a novel two-way valve placed in the apparatus between the liquid tank and the service hose and the adapter, which is described in my application for patent, on an Adapter bushing, Serial No. 13,201, filed March 27, 1935, and this valve is for reversing the direction of flow of liquid through the service hose to alternately force the liquid into the crank-case pan, and then without loss of time to reverse the direction of flow and withdraw the liquid and the sediment which has become mixed with it from the pan, repeating these injections and withdrawals for the desired number of times to effect the removal of all of the old lubricant, dirt and sediment from the pan.

This is accomplished by rotating the valve by suitable gearing from the motor, this valve is not alternated back and forth, (as described in my application for patent, on a Crank and gear case cleaning apparatus, Serial No. 754,025, filed November 21, 1934) but continues to revolve in one direction only, and the ports are so designed that the inlet and outlet are closed equally and opened equally so that the pump is relieved of all back pressure, and the ratio is such that by employing an alternating current motor having a constant speed, of say, 1800 R. P. M., the fluid will be forced into, and remain in the crank-case for a predetermined length of time, and these injections and withdrawals being alternated for as many times as are required to clean the crank-case. Should a direct current motor be employed, it should be of the shunt type, having a constant speed, as the operation of the valve is in direct ratio to the speed of the motor.

I have also incorporated in the apparatus means whereby the liquid in the container is subjected to two different degrees of heat, the maximum or high heat for quickly raising the temperature of the liquid, and the minimum degree of heat for retaining the temperature without the

maximum consumption of electric current; this control being under thermostatic regulation.

The low heater coil is energized by turning on the electric current from the main and before any current is supplied to the motor, and thus the fluid in the container is first preheated. Then by the manipulation of the double pole switch the current is admitted to the motor to operate the pump and valve, and at the same time the high heater is energized, thus quickly increasing the temperature of the fluid, and should the temperature become too high, the current is automatically cut off by a thermostat.

In the separation of the sediment from the liquid, I have employed a centrifuge through which the liquid is forced to travel between each withdrawal and injection, and in place of having to remove the bowl of the centrifuge for cleaning out the deposit, I have provided a bowl with a renewable lining of fabric in the form of a bag, which when filled with dirt and grit, etc., can be removed and a clean one inserted in its place, or the dirt washed out and the bag replaced.

Also I have provided a transparent dome through which all of the liquid has to pass and where it may be seen at all times to determine its condition, and a suitable fluid level indicator to show the amount of fluid in the container.

There may also be added lights to indicate which heater is on, the low or high.

In the drawings:

Figure 1 is a vertical sectional view of my device, showing the arrangement of the several parts.

Figure 2 is a longitudinal sectional view taken on the line 2—2 of Figure 1, looking downward, showing the upper side of the deck and gearing.

Figure 3 is a similar view, but taken on the line 3—3 and looking upward.

Figure 4 is an enlarged detail plan view of the pump.

Figure 5 is an enlarged detail longitudinal sectional view of the two-way valve during the first suction period.

Figure 6 is an enlarged detail, partial vertical view of the valve.

Figure 7 is a view taken on the line 7—7 of Figure 1, showing the inside of the duct member.

Figure 8 is a partial sectional view of the service hose, adapter, and crank-case.

Figure 9 shows an electrical wiring diagram of the apparatus.

Figure 10 is a schematic drawing of the device.

Figure 11 is a detail sectional view of the centrifuge, showing the renewable sediment bag.

Referring to the drawings:

I have indicated an outer casing 10 of suitable sheet material, either round, square, or rectangular, but which is here shown as round, and within the lower end of which is secured a bottom supporting ring 11, provided with the feet 12 and the bearings 13 for the shaft 14 upon which the traction wheels 15 are mounted.

The upper end of the casing 10 is closed by a cover plate 17 which is hinged thereto as at 18 and secured by a latch 19.

About midway between the ends, within said casing 10 is secured upon the ring 20, a deck 21.

Below this deck 21 and to the underside thereof are secured the upper ends of the motor supporting legs 22 which are attached at their lower ends to the motor 24; the rotor shaft 25 of the motor 24 is coupled by a universal joint 26 to the vertical drive shaft 27 which extends upwards through an opening in the deck 21 and

operates the pump 28, the centrifuge 38, and through a train of gears, the valve 29.

Upon the upper side of the deck 21 is secured a tubular can 32, resting upon a gasket 33 to provide a tight joint and forming a liquid chamber 5 therein.

Also upon the upper side of the deck 21 is formed a bearing 35 for the drive shaft 27 and secured to the deck 21 is a support 36 having a bearing 37 for the vertical shaft 27. Upon the upper end of this shaft 27 is detachably mounted the centrifuge bowl 38 by the boss 39 and screw 40.

This bowl 38 is formed with an open upper end and inwardly tapered sides terminating in a beaded edge 38' and provided with a series of radial openings 23 in the side adjacent to the bottom; while within this bowl 38 is secured a screen backing 41 and a renewable fabric bag 150.

Embracing this bowl 38 is an inner tubular can 42, set with a bottom composed of a flat 20 portion 43, an inclined portion 47, and an upwardly extending tubular collar portion 46; and having a central opening and a lower flange 49 surrounding the lower part of the bowl 38 and spaced therefrom.

The cover plate 17 is formed with a central opening 51, and a sight hole 52 affording a view of an indicator flush gage and a fluid level indicator.

This central opening 51 has a threaded collar 54 for a sight feed dome 55 of glass, and the lower face of the cover 17 is formed with a duct 56 leading from the boss 51 to and discharging into the central opening 51 and glass dome 55. Attached to the lower face of the cover 17 is a filler can and splash guard 58 with a funnel 60; the funnel 60 has a breather pipe 61.

If desired this cover plate 17 may be rectangular and flat, and the glass dome 55 may be located directly above the upper end of the pipe 40 62 and have a funnel leading to the centrifuge 38.

The cover plate 17 may also be formed with an opening directly above and affording access to the bowl 38 and through which the liquid may be entered when loading the device.

On this plate 17 may also be mounted the injection counter and an oil level gage as well as two lights to indicate if the low or high heat is on.

Secured to the flat portion 43 of the bottom of the can 42 is a lower can 31 which has an inclined bottom 50 and a flat bottom 63 of wire mesh to form a strainer, through which the oil may pass to the heater, and this bottom 63 is also provided with a central opening having an upstanding annular collar 155, surrounding the bearing 37. This can 31 is also embraced by the outer can 32 which forms the liquid chamber 34.

To eliminate the trouble caused by the use of piping between the several parts to convey the liquid, I have employed a duct member plate 66 which is formed with ducts or passages for the liquid, and which is secured to the bottom face of the deck 21 by a gasket 67 and a series of bolts 68; and to this duct member 66 are secured the gear pump 28 and the valve 29; while one end of said member 66 is provided with a drain cock 69 extending through the side of the casing 10 and communicating with a duct 83.

This duct member 66 is formed with the ducts 70, 71, and 72, and the openings 73, and 74 which communicate with the pump 28 and also the openings 75, 76, and 151 which communicate with the ports of the valve 29.

Mounted on the deck 21 and communicating 75

with the duct 78 of the member 66, is a check valve 78, to which is attached the lower end of the inner telescoping tube or pipe 79; the upper section 62 of which rests upon the spring 81 which 5 retains the said pipe 62 tight within the boss 57 when the cover 17 is closed.

Also mounted upon the deck 21 is secured a second check valve 82 which communicates with the duct 70 in the member 66.

10 Adjacent to these check valves 78 and 82, the deck 21 is formed with two openings which lead to the duct 84 in the member 66, which communicates with the drain cock 69 for draining the chamber 34 within the casing or can 32.

15 The support 36 is provided with a bearing 86 in aligned relation with a bearing 89 on the deck 21, and within these bearings 86 and 89 is rotatably mounted a shaft 90 upon which is mounted a worm wheel 80 rotated by a worm 92 on the drive shaft 27. A worm 93 is also secured on the shaft 90 to rotate a worm wheel 94 on the shaft 95 of the valve 29 mounted in the bracket 96 on the deck 21 for rotating the valve rotor of the multiple port valve 29.

20 25 This valve 29 is of special design as it operates in the liquid, and as the sediment and grit from the crank-case passes through on the suction period of the cycle, they would clog and damage the usual type of valve and cause it to be either 30 scored or jammed.

To overcome this disadvantage, I have designed a valve having a body 29 formed with four radial bosses 97, 98, 99 and 100; the bosses 97 and 98 having closed ends; the boss 99 having its 35 end closed by the plug 101 and the boss 100 being connected to the pipe 102.

The bosses 97, 98, and 99 are formed with the openings or ducts 103, 104, and 105 therein, and 40 register with the ducts or openings 75, 76, and 151 in the member 66. The bosses 97, 98, 99, and 100 are also formed with radial ducts 106, 107, 108, and 109, all of which communicate with the central valve core, within which is rotatably mounted the valve rotor 110 secured on the shaft 45 111 and formed with the two ports 112 and 113. The ducts 106, 107, and 108 also communicate with the ducts 103, 104, and 105.

To prevent the valve 29 from being scored as 50 well as the core 110 by the foreign matter passing therethrough, I have provided this core 110 with two grooves 114, and have beveled the corners as at 115 leaving openings, and have provided a tube 116 extending from one corner of the core 110 to and into the liquid chamber 34 so 55 that lubricant is fed to the core 110 and foreign matter entering the valve can be carried off through the grooves 114, corner openings 115 and the tube 116; the core 110 being rotated in one direction only.

60 During the first injection, the port 112 of the valve rotor 110 registers with the ports 108 and 107 of the body 29; while the port 113 of the valve rotor 110 registers with the ports 106 and 109 of the valve body 29. When the rotor has 65 revolved for another quarter turn for the first suction period which immediately follows the injection period, the port 112 registers with the ports 106 and 107; while the port 113 registers with the ports 108 and 109, thus completing the 70 port positions for one cleaning cycle. As the valve continues to rotate for a third quarter turn to begin the second injection, and the start of another cleaning cycle, the port 112 registers with the ports 106 and 109; while the port 113 75 registers with the ports 107 and 108, and, when

the rotor makes the fourth quarter turn for the second suction stroke which will complete the second cleaning cycle, the port 112 is in registry with the ports 108 and 109 at the same time that the port 113 is registering with the ports 106 and 107.

The liquid pump 28 is of the gear type and comprises the casing and cover; while the interior is formed with the intake 117 and outlet 118 and within which are mounted the impeller gears 119 and 120, which are of special design, having their teeth so shaped that there is considerable space between the back face of the teeth of one gear and the front face of the teeth of the opposing gear, so that any dirt or particles of foreign matter can pass between the teeth of the gears without damage or stoppage of the pump; the gear 119 is mounted on a stud 121 and the gear 120 is secured on the shaft 27.

I have also provided a visual counter 64 for 20 recording the number of rotations of the valve 29; that is, the number of cleaning cycles; and this comprises a dial 64 on the can 42 which is visible through an opening 52 in the cover 17, and in connection with this dial 64 is a hand 122 25 secured on the upper end of a rod 123; the lower end of which is journaled in the bracket 96 and has a gear 124 secured thereon and rotated by a pinion 125 on the shaft 95.

To determine the amount of fluid in the chamber 34, I have provided a suitable fluid level gage of the usual float type, having a vertical rod 126 with a pointer 127 attached to the upper end over a dial mounted in the upper part of the apparatus, a float not shown being secured 35 on the lower end of the rod 126.

For heating the liquid in the chamber 34, I have provided an electric induction heater 128 of novel design, similar to that described in my Patent No. 1,999,446, issued on April 30, 1935, for 40 a Transformer coupled induction heater. I have mounted this in the lower part of the chamber 34, surrounding the support 36 and secured to the deck 21 by a tubular leg 129 through which the electric wires are carried through a suitable 45 switch 130 and a thermostatic control 131, from a current supply plug.

Referring to the wiring diagram, Figure 9, a current input plug 132 is shown which is to be connected to the current supply and from this 50 in one lead 133 to the motor 24 and thermostat 131, and another lead 134 to the common terminal 135 of a double pole switch 136.

From this terminal 135, a wire 137 is connected to a low heater 138 which is connected by a wire 55 139 to one terminal of the high heater 153 and by a wire 152 to one terminal of the switch 136; the other terminal of the high heater 153 being connected to one terminal of the thermostat 131. The circuits are completed by a wire 154 from 60 the motor 24 to the switch 136.

In the operation of the device, a clean filter bag 150 is inserted into the centrifuge 38 and the required quantity of cleaning fluid introduced through the can 58, the centrifuge 38 and can 31, 65 into the chamber 34, submerging and surrounding the heater 128 to the level indicated.

The electric current is admitted through the plug 132 supplying current to the low heater 138 without operating the motor 24, and in this manner the fluid is warmed up.

Since the thermostat 131 is closed when the connection 132 is plugged into the current line, both heaters will be operating in series according to Figure 9, which fact will produce the low 75

heat. When the switch 136 is closed, the heaters will be acting in parallel and since the resistance will be lowered, the heat will be greater.

The service hose 140 is now connected by the 5 adapter 141 to the drain opening of the crank-case 142 (the case 142 having first been drained) and the switch 136 is now closed, supplying current to both the motor 24 and the high heater 153.

10 The motor shaft 27 operating the pump 28 to draw the heated fluid from the chamber 34 through the check valve 82 in the deck 21, duct 10 and the hole 151 in the member 66, and then through the ducts 104, 107, 112, 108, and 105 in 15 the valve 29; hole 75, duct 71, and hole 73 in the member 66 to the intake 117 of the pump 28, through the exhaust 118 of the pump, and then the ducts and holes 74, 72, and 76 in the member 66, to the ducts 103, 106, 113, 109, of the valve 29; and through the pipe 102 and service hose 140, and adapter 141 to the crank-case 142. While at the same time, the motor shaft 27, 20 through the gearing 80, 92, 93, and 94 is rotating the valve core 110 to change the direction of flow 25 of the fluid therethrough, to withdraw the fluid from the crank-case 142 through the adapter 141, service hose 140, and pipe 102 to the ducts 109, 113, 108, and 105 of the valve 29, and through the hole 75, duct 71, and hole 73 in the member 30 66 to the intake 117 of the pump 28 and through said pump 28 and out the exhaust 118 to the hole 74, duct 72 and hole 76 of the member 66 to the ducts or ports 103, 106, 112, 107, and 104 of the valve 29, and through hole 151, duct 70 35 of the member 66, upwards through the check valve 78 in the deck 21, and through the telescoping pipes 79 and 62, and the duct 56 in the cover plate 17 to the glass dome 55, and down through the filter bag 150, where it is then driven 40 through the centrifuge 38 into the chamber 34.

Through the gears 124 and 125, each rotation of the valve 29 is indicated by the counter 64; and, by the float 127 in the chamber 34, the fluid level is indicated on the gage 127.

45 After the required number of injections and withdrawals have been completed, the current may be cut off and the fluid drained from the chamber 34 by the drain cock 69 and the filter bag 150 may be removed from the centrifuge 38 for cleaning or for replacement by a new bag.

50 Should the fluid become too hot, the flow of current through the heater 153 is cut off by the action of the thermostat 131, which breaks the circuit from the wire 133 through the switch 136 of the wire 134 and cuts out the high heater 153 leaving the low heater 138 energized through the wire 133, motor 24, double pole switch 136 and wire 137.

Having thus described my invention, what I 60 claim is new and desire to secure by Letters Patent, is:—

1. In an apparatus for cleaning crank-cases of the class described, comprising a cleaning fluid supply container, a motor driven pump for causing the fluid to travel, a valve having a series of ports for directing the direction of travel, means actuated by and timed in relation to the speed of the motor for operating said valve to reverse the direction of flow of the fluid through said valve, a single duct tubular connection between the valve and the crank-case through which the fluid passes in either direction, a centrifuge having a strainer member interposed between the valve

and the fluid intake and driven by the motor, a renewable filter for said strainer member, and means for heating the fluid while within the fluid supply container.

2. In a crank-case cleaning apparatus, comprising a cleaning fluid supply container, and a single duct tubular connection for conveying the fluid to the crank-case, a motor driven pump for causing the fluid to flow through said single tubular connection, means mounted in the path of 10 flow of said fluid for reversing the direction of flow of fluid through the tubular connection, means timed in direct ratio to the speed of the motor for actuating said flow reversing means, means for centrifuging and straining the fluid, 15 and means for heating the fluid while within the container.

3. In a crank-case cleaning apparatus of the class described comprising a liquid container and a valve said valve having a single duct tubular 20 connection with the crank-case, means for injecting into and withdrawing the liquid from the crank-case through the single tubular connection to the valve, means in mechanically timed relation for alternating the injections and withdrawals, means for normally heating the liquid, means for increasing the temperature during the injection and withdrawal periods, and means for centrifuging the liquid each time upon its withdrawal from the crank-case.

4. In a crank-case cleaning apparatus, comprising a cleaning fluid supply container and a valve, a single duct connection for conveying the fluid back and forth between the fluid valve and the crank-case, a single motor driven pump for causing the fluid to travel through the connection, a rotary multi-port valve mounted in the path of travel of the fluid, means mechanically timed for alternating the direction of flow of fluid through said valve.

5. In a crank-case cleaner apparatus, comprising a cleaning fluid supply container and a valve, a single duct tubular connection between the valve and the crankcase for conveying the fluid to and from the crank-case, a motor driven pump for circulating the fluid through said tubular connection, a reversible valve located in the path of travel of the fluid, means mechanically timed and actuated by the motor and timed in positive ratio thereto for directing the flow through different paths in said valve for reversing the flow of fluid therethrough, means for cleaning the fluid after each withdrawal from the crank-case, comprising a centrifuge having an open end to receive the fluid, a perforated side for the escape 55 of the cleaned fluid and a renewable filtering medium within the centrifuge.

6. In a crank case cleaning apparatus, comprising a cleaning fluid supply container having a control valve therefor and a single duct tubular 60 connection between said valve and the crank case, a motor driven pump for causing the liquid to travel through said tubular connection, means mounted in the path of said travel for reversing the direction of flow, means timed in direct ratio to the speed of the motor for actuating said flow reversing means, means for centrifuging and straining the fluid after each withdrawal from the crank case, and means for heating the liquid 65 while within the container.

JAMES K. DELANO.
